(57) CLAIM

The ornamental design for a shoe, as shown and described.

DESCRIPTION

FIG. 1 is a front elevational view of a shoe showing my new design;

FIG. 2 is a rear elevational view thereof;

FIG. 3 is a side view, taken from the left side of FIG. 1; FIG. 4 is a side view, taken from the right side of FIG. 1; FIG. 5 is a top plan view thereof; and, FIG. 6 is a bottom plan view thereof.

The dotted lines showing a sole, shoelace and cuff in the figures are for illustrative purposes only and form no part of my invention.
